PROCESSING ALKYL ESTERS OF FATTY ACIDS

Charles G. Goebel, Cincinnati, Ohio, assignor to
Emery Industries, Inc., a corporation of OhioNo Drawing. Application October 6, 1951,
Serial No. 250,199

6 Claims. (Cl. 260—416)

This invention relates to a method of hydrolyzing the 15 esters of higher fatty acids and volatile monohydric alcohols and to the utilization of this process in the manufacture of fatty acids.

In the manufacture of the higher fatty acids from naturally-occurring fats and oils, which consist of the 20 glycerol esters of the various fatty acids, ranging in chain length from 12 to 22 carbon atoms, one of the first steps is to hydrolyze the ester to produce glycerine and free fatty acids. One method of accomplishing this is by the Twitchell method in which the fat or oil is boiled with water in the presence of a small amount of inorganic acid, usually sulfuric, and a small amount of a Twitchell reagent, which promotes contact between the oil and water phases and catalyzes the reaction. The hydrolysis reaction is reversible and care must be taken that the concentration of glycerine in the water phase does not become too great or the hydrolysis, or splitting as it is usually termed, will be incomplete. In practice, it has been found practical and efficient to obtain a high degree of split by supplying a fresh charge of water after the hydrolysis is about 85% complete. The second charge of water reduces the glycerine concentration and fats can be split to 95% to 97% free fatty acid content without difficulty.

It has also been proposed to liberate the glycerine from fats by heating with monohydric alcohols such as methanol. By this process, known as alcoholysis, the glycerine is liberated but instead of forming fatty acids, the esters of the fatty acids and the alcohol used in the process result. The alcoholysis process is easily carried out and has been proposed as a step in the manufacture of soap, but in fatty acid manufacture the free acids are the products desired for commercial use and the alcoholysis process has not been practiced because of the difficulty of decomposing the esters to obtain the free acids. Also, it has been proposed that fatty acids or glycerides be converted to esters to facilitate modifying treatments which are more destructive to the acid than the ester, but here, too, the difficulty of reconversion has been a stumbling block. Efforts to accomplish the split by the normal Twitchell method and the normal pressure splitting method have been equally unsatisfactory when directed to these synthetic esters because very little hydrolysis results, and the only method which has been found chemically effective has been to first react the ester with a strong alkali, such as sodium hydroxide, and then liberate the free acids by decomposing the resulting soap with mineral acid. This two step process is costly in that expensive caustic and acid are both used and the only by-product is a relatively worthless salt.

It is the purpose of this invention to provide a method whereby the esters of the higher fatty acids and volatile monohydric alcohols may be hydrolyzed cheaply and conveniently by a single step process.

It is the further purpose of this invention to provide a process which may be utilized in the commercial production of fatty acids with a saving in equipment costs.

I have found that the esters of fatty acids and volatile monohydric alcohols can be split by a method akin to the Twitchell method, that is, by boiling with water, mineral acid and a Twitchell reagent, but to accomplish 5 the result the concentration of the alcohol in the water layer must be kept to a very low percentage, much below the concentration of glycerine which is usual in the splitting of glycerol esters.

This can be accomplished by the use of large quantities 10 or several changes of water which will also necessitate the use of additional acid and Twitchell reagent, if the latter is of the type having an appreciable water solubility. I have found that a much more convenient and less expensive method is to remove the water vapor, which results from the boiling operation, from the splitting vessel in order that the alcohol resulting from the hydrolysis may be removed substantially as fast as it is formed, and adding water to the splitting vessel continuously or from time to time to replace that removed as vapor. If open steam is employed for boiling, as is generally the case in the practice of Twitchell splitting, the steam is merely allowed to bubble through the charge and out of the vessel. The vapors may either be allowed to escape to the atmosphere or totally condensed in a condenser or passed through a fractionating tower which will permit the removal and recovery of the alcohol while the water may either be returned to the vessel or discarded.

My process can be employed using the esters of a fatty acid and any volatile alcohol. As the boiling point of 30 the alcohol increases, the time and/or the amount of water vapor which must be removed from the splitting vessel, in order to remove the alcohol, also increases. Therefore, for practical purposes, the process is limited to monohydric alcohols of not over eight carbon atoms or other ester forming alcohols which boil or vaporize at or below the boiling point of water or are removed with the water vapor. Since my process is directed toward a method of decomposing esters and would not find utility where a particular ester is to be sold as an article of commerce, it is most economically practiced with the methyl ester, which is cheap, easily prepared and requires the least weight of alcohol per pound of fatty acid. Also, the methyl alcohol has a low boiling point.

The amount of water initially charged into the hydrolysis vessel is relatively unimportant, as its only function is to provide contact with the ester phase. About 45 25% of the weight of the ester may be sufficient, although greater or lesser amounts may be used, depending upon the shape of the reaction vessel and other conditions. The amount of steam or water vapor removed from the hydrolysis vessel should be great enough to effect sufficient continuous removal of the alcohol to maintain maximum rate of hydrolysis. If the rate of removal is too low, the only effect is to prolong the time of hydrolysis; too high a rate has no adverse effect other than being wasteful. With methyl esters, the removal of 7.5% of water per hour, based on the weight of the ester, shows a slight retardation of hydrolysis, while removal of 12.5% insures no retardation of the reaction 55 and is as effective as 25%.

The water in the hydrolysis vessel must be acidic to obtain hydrolysis. From .5% to 2% of sulfuric acid 60 may be used or organic sulfonic acids such as para toluene sulfonic acid may be substituted in whole or in part. From 1% to 2% of Twitchell reagent based on the weight of the ester is used. This may be a sulfonated fatty acid aromatic ring condensation product, the sulfonic acids derived from petroleum known as mahogany acids, or synthetic alkyl aryl sulfonic acids. Their purpose is to catalyze the hydrolysis, the same function that they perform in the normal Twitchell method of fat 70

hydrolysis. By carrying out the hydrolysis as described, 95% to 97.5% hydrolysis of fatty acid esters can be achieved. The boiling time may range from 7 to 8 hours for methyl esters to as high as 45 hours for esters of octyl alcohol.

The difference between the problem of splitting glyceryl esters and that of splitting synthetic esters is crystallized by the observation that a normal Twitchell split of glyceryl esters which will result in 95% to 97% hydrolysis after two boils of six hours each, when applied to methyl oleate, will result in only about 60% to 65% hydrolysis. The great difference in degree of hydrolysis achieved might be explained by simply assuming that the monohydric alcohol esters are more stable than the glyceryl esters. I believe, however, that the difference is explained by my discovery of the surprisingly great effect of low concentration of monohydric alcohols in retarding the hydrolysis of esters. To confirm this, I have determined the equilibrium constant involved in the hydrolysis of methyl oleate and find that the formula

$$\frac{\% \text{ concentration alcohol in water}}{\% \text{ unsplit material in ester layer}} = K$$

gives a K value of .0596, whereas when the ester is a glyceryl ester and the liberated alcohol is glycerine, the value of K is 1.28 or almost 24 times as great. In other words, the concentration of methyl alcohol in the water layer must be kept down to $\frac{1}{24}$ of the concentration of glycerine to obtain an equivalent degree of hydrolysis.

My discovery of an inexpensive and efficient method of hydrolyzing the alkyl esters also comprehends a new method for the manufacture of fatty acids. The glyceryl esters of fatty acids, or as commonly termed fats or oils, may be subjected to an alcoholysis reaction, in accordance with procedures well known in the art, to make preferably the methyl esters. The various steps of purification and separation, such as distillation, fractional distillation, fractional precipitation or hydrogenation may then be carried out on the methyl esters, which as a final step, can then be converted to the acids by my hydrolysis procedure. The methyl esters have lower boiling points than the acids, a property which is advantageous in conducting distillation, but a far greater advantage resides in the fact that since the esters are neutral and non-corrosive, all of the processing steps up to the final hydrolysis step can be carried out in ordinary steel equipment. Fatty acids, particularly at elevated temperatures, are quite corrosive and it is necessary to employ expensive materials of construction, such as Monel metal and stainless steel, and in spite of the use of such metals, maintenance and repair costs are high. Processing neutral esters not only greatly reduces the cost of initial investment in equipment, but also effects economies in operating costs.

In ordinary Twitchell splitting of the fatty glycerides, it is conventional to utilize a Twitchell reagent which is more fat soluble than water soluble. The reason for this is that if the Twitchell reagent were more water soluble than fat soluble, it would go into the glycerine water and constitute a contamination which would be very difficult to remove economically. On this account, the solubility of the Twitchell reagent is so chosen that the reagent is dissolved in the fatty acids layer after completion of the split, then the reagent and the fatty acids are easily separated by the distillation which is conventionally used after a Twitchell split. This results in total loss of reagent.

In the Twitchell splitting of the alkyl esters, the two layers which form after the split are constituted respectively by fatty acids and water, the alcohol having been driven off during the splitting. Since there is no problem of glycerine contamination, it is preferable to use a water soluble Twitchell reagent which at the finish of the splitting operation is dissolved in the water layer rather than in the fatty acids layer. This selection accomplishes two things.

First, the fatty acids are not contaminated with the splitting reagent and do not require distillation for the purpose of purifying them, particularly if they have already been distilled in the form of the methyl esters.

In the second place, the utilization of the water soluble Twitchell reagent makes it possible to use one solution of Twitchell reagent in water over and over again for successive batches of alkyl esters of fatty acids, so that there are no splitting reagent costs over and above those requisite for the first batch.

These preferentially water soluble reagents are the lower molecular weight members of any given class of Twitchell reagent. Exact limits of molecular weight cannot be given because solubility varies with molecular configuration, but in any case, a properly water soluble Twitchell reagent may be easily and readily determined by routine empirical solubility test in the laboratory.

The following examples further illustrate the practice of my invention:

20 *Example 1.*—300 parts of methyl oleate, 300 parts of water, 3 parts of mahogany sulfonate and 3 parts of 66° B. sulfuric acid were heated for 8 hours during which time 500 parts of water were evolved which were replaced, as evolved, by fresh water. At the end of the 25 eight-hour boil, the fatty layer was separated and analyzed 96% free oleic acid.

As a comparison, the same proportions of reactants were boiled for six hours without allowing the escape of water or the liberated methyl alcohol.

30 At the end of this treatment, the fatty acid content of the fatty layer analyzed only 43.3% oleic acid. The water layer was then drawn off and the same amount of fresh water and acid added. After boiling for an additional six hours, the oleic acid content had increased 35 to only 59.5%.

35 *Example 2.*—200 parts of methyl undecylenate were boiled for seven hours with 200 parts of water, 2 parts of mineral oil sulfonates and 2 parts of sulfuric acid. Steam and liberated alcohol were allowed to escape and 40 replaced by the addition of fresh water. At the end of seven hours, the fatty layer contained 97.5% free undecylenic acid.

45 *Example 3.*—The process of Example 2 was carried out with propyl oleate. At the end of 14 hours, the hydrolysis was 95.8% complete.

50 *Example 4.*—Butyl stearate was hydrolyzed as described in Example 2. After 14 hours, hydrolysis was 96.2% complete.

55 *Example 5.*—Methyl isobutyl carbinol stearate was processed as described and after 32 hours, was 95.1% hydrolyzed and 2 ethyl hexyl oleate (octyl oleate) was 60 94.8% hydrolyzed after 45 hours.

60 *Example 6.*—300 parts of methyl oleate, 300 parts of water, 3 parts of para toluene sulfonic acid and 1.5 parts of oil soluble petroleum sulfonates were boiled for 12 hours, replacing the evolved water. At the end of this period, the fatty layer analyzed 96.9% oleic acid. The acids were bleached with 3% of acid activated bleaching earth yielding oleic acid with a color comparable to that 65 of the average distilled oleic acid. As previously indicated, water soluble petroleum sulfonates may be used in place of the oil soluble sulfonates.

65 *Example 7.*—Cottonseed oil was subjected to methylolysis in the presence of an alkaline catalyst. The glycerine layer was removed and the methyl esters dried and 70 fractionally distilled to obtain one fraction consisting essentially of methyl palmitate and a remaining fraction consisting of a mixture of the methyl esters of oleic, linoleic and stearic acids. The methyl palmitate fraction was hydrolyzed as described in Example 2 and bleached to 75 yield a commercially pure palmitic acid. The other fraction was hydrogenated by conventional methods and then hydrolyzed and bleached as previously described to yield a light-colored solid acid consisting mainly of stearic acid.

Example 8.—250 parts of dimethyl ester of dimer acids produced by the polymerization of unsaturated fatty acids, 250 parts of water, 2½ parts of para toluene sulfonic acid, 2½ parts of 50% water soluble petroleum sulfonates were boiled for 12 hours, during which time 1,000 parts of water were passed through the boiling mixture. At the end of this time, the original free fatty acid of 4.88% calculated as oleic, had increased to 85% calculated as oleic. Completely saponified methyl ester showed a free fatty acid content of 91.5% as oleic acid so that the per cent hydrolysis obtained was 93%. The original ester had a color of 12 Gardener and the acids recovered after bleaching had a color of 14 Gardener.

By the method herein disclosed, it is possible to convert the alkyl esters of the higher fatty acids directly to the fatty acids by means of a single processing step which in and of itself is no more difficult or expensive than the conventional hydrolysis of the fatty triglycerides. In fact, this process is no different from the Twitchell process except for the fact that the boiling mixture is sufficiently heated to positively remove appreciable quantities of vapor, which degree of heating would be sheer waste in the conventional Twitchell process, and the water removed as vapor is replaced which in the conventional Twitchell process is unnecessary.

Hence, wherever it is desirable for any reason whatsoever to treat, condition, react or modify fatty bodies as alkyl esters, such treatment may be readily accomplished by converting either the triglycerides or the acids to the alkyl esters before such treatment and the alkyl esters may, by the process of this invention, be converted back to the acids after such treatment.

Having described my invention, I claim:

1. A process for the hydrolysis of the esters of volatile monohydric alcohols and higher fatty acids, of 12-22 carbon atoms chain length which comprises boiling the esters with water containing a Twitchell reagent and an acidifying reagent, allowing water vapor and the alcohol liberated by the hydrolysis to escape continuously, continuously replenishing the evolved water and continuing the boiling until the desired degree of hydrolysis is attained.

2. A process for the manufacture of higher fatty acids,

consisting of the steps of subjecting a fat or oil to methanolysis separating the liberated glycerine from the methyl esters, further processing the methyl esters to effect purification and separation, and then liberating and recovering the fatty acids by subjecting the esters to a Twitchell hydrolysis carried out under conditions permitting the continuous evolution of water vapor and methyl alcohol liberated by the hydrolysis and replacement of the evaporated water.

3. A process for the hydrolysis of the esters of higher fatty acids, containing 12-22 carbon atoms, and monohydric alcohols containing from 1 to 8 carbon atoms, comprising boiling together the ester and from 25% to 100% by weight of water, from .5 to 2% of a Twitchell reagent and from .5 to 3% of mineral acid, and passing steam through the boiling mixture at the rate of from 7% to 25% by weight of the ester per hour for a period of from 6 to 48 hours, removing alcohol as formed and replacing water as evaporated.

4. A process for hydrolyzing the esters of higher fatty acids and volatile monohydric alcohols by the Twitchell method in which the volatile alcohols liberated by the hydrolysis are removed by vaporization as rapidly as liberated and the water evaporated is replaced.

5. The method of manufacturing the higher aliphatic fatty acids of from 12 to 22 carbons chain length from their corresponding alkyl esters, said method comprising Twitchellizing said alkyl esters by heating sufficiently to remove appreciable water as vapor and alcohol as formed and replacing the water thus lost by vaporization.

6. The method of manufacturing the higher aliphatic fatty acids of from 12 to 22 carbons chain length from their corresponding alkyl esters, said method comprising boiling said alkyl esters in water which contains relatively water soluble, fatty acid insoluble, Twitchell reagent, removing alcohol as formed and replacing water as vaporized.
